SIEGFRIED VON AMMON, OF BOWDON, ENGLAND, ASSIGNOR, BY MESNE ASSIGNMENTS, TO WESTINGHOUSE ELECTRIC & MANUFACTURING COMPANY, OF EAST PITTSBURGH, PENNSYLVANIA, A CORPORATION OF PENNSYLVANIA.

COMMUTATOR FOR ELECTRICAL MACHINES.

1,018,544.

Specification of Letters Patent.

Patented Feb. 27, 1912.

Application filed April 10, 1908. Serial No. 426,364.

To all whom it may concern:

Be it known that I, SIEGFRIED VON AMMON, a subject of the Kingdom of Prussia, and a resident of Bowdon, in the county of 5 Chester, England, have invented a new and useful Improvement in Commutators for Electrical Machines, of which the following is a specification.

My invention relates to commutators for 10 electrical machines and in particular to commutators, the segments of which are held in position by shrink rings or other bands passing around their exterior surfaces. In this 15 type of commutator, short-circuiting of the segments by the shrink rings must necessarily be prevented by interposing insulating material between the shrink rings and the segments, but difficulty has heretofore been experienced in insulating the lateral 20 or plane surfaces of the rings in order to prevent arcs occurring between the segments and the rings or between the brushes and the rings. This difficulty is greatly increased 25 in the case of grooved commutators intended to be run at a high speed, in which case, the peripheral speed of the shrink rings is very high.

According to my present invention, in 30 order to overcome the difficulties above mentioned, I insulate the shrink rings or bands by means of annular plates or shields of insulating material of any suitable form, which do not rotate with the commutator but are supported from a fixed part of the 35 machine at a suitable distance from the surfaces of the shrink rings which it is desired to guard.

The invention is illustrated in the single 40 figure of the accompanying drawings which is a sectional view of one half of a commutator embodying the invention.

Referring now to the figure, the shaft 1 of the electrical machine is provided with conical bushings 3 which support a commutator 45 comprising a plurality of insulated segments 2, insulating rings 4 being interposed between the segments 2 and the bushings 3. The segments 2 are held together by means of shrink rings 5 and 6 located at 50 the respective ends of the segments 2 and by a central shrink ring 7, insulating rings 8 being provided to prevent the commutator segments from being short-circuited by the shrink rings.

As illustrated in the drawing, the commutator is of the grooved type, being provided with brushes 9 that are adapted to make contact with the radial faces of the commutator grooves. The brushes 9 are carried by brush holders 10 which are supported from 60 brush rings 12 by a brush arm 11. In order to prevent arcs occurring between the segments 2 or between the brushes 9 and the shrink rings 5, 6, and 7, stationary annular plates or shields 13 of insulating material 65 are provided which are attached to the brush arm 11 and to the brush rings 12, as shown, but which may be supported in any other suitable manner. The inner edges of the annular plates 13 are located in grooves 14 70 in the commutator segments 2 and may be of any suitable hard insulating material, such, for example, as vulcanized fiber or micanite.

It will be understood that, if desired, the 75 inner edges of the shields 13 and the portions of the commutator segments which are engaged thereby may be modified as to form from what is shown, if desired.

Other modifications from the precise ar- 80 rangements herein shown and described may evidently be made without departing from the spirit and scope of the invention.

I claim as my invention:

1. A commutator for dynamo-electric ma- 85 chines comprising segments or bars, a plurality of clamping rings surrounding said segments or bars and insulated therefrom and stationary annular plates or shields of insulating material located adjacent to the 90 said rings, for the purpose specified.

2. A commutator for a dynamo-electric machine provided with stationary annular insulating plates or shields located between 95 commutator brushes and disposed in planes perpendicular to the commutator cylinder axis.

3. In a dynamo-electric machine, the combination with a commutator cylinder and brushes in engagement therewith, of sta- 100 tionary annular insulating barriers between the brushes.

4. In a dynamo-electric machine, the combination with a commutator cylinder and brushes in engagement therewith, of a pair 105 of stationary annular insulating barriers between adjacent sets of brushes.

5. In a dynamo-electric machine, the com-

bination with a commutator cylinder having a plurality of insulated segments, and brushes in engagement with the commutator cylinder surface, of annular barriers of 5 insulating material disposed between the brushes and stationary relative to the commutator cylinder.

6. In a dynamo-electric machine, the combination with a commutator cylinder comprising a plurality of insulated segments and bands or shrink rings for holding the segments in position, of stationary brushes 10 that engage the surface of the commutator cylinder between the rings, and stationary 15 insulating barriers between the rings and the brushes.

7. In a dynamo-electric machine, the combination with a commutator cylinder comprising a plurality of insulated segments 20 and metal bands or shrink rings for holding the segments in position, said bands or rings being insulated from the segments, of stationary supporting rods substantially parallel to the axis of the commutator, 25 brushes engaging the commutator cylinder, brush supporting arms secured to the stationary rods, and annular barriers of insulating material secured to the stationary rods and located between the brushes and 30 the metal bands or rings.

8. In a dynamo-electric machine, the combination with a commutator cylinder having a plurality of annular recesses, and stationary brushes engaging the walls of said recesses, of stationary insulating barriers be- 35

tween the recesses, the inner edges of which are adjacent to the commutator cylinder.

9. In a dynamo-electric machine, the combination with a commutator cylinder comprising a plurality of insulated segments 40 and having annular recesses, of bands or shrink rings for holding the segments in position, stationary brushes that engage the walls of the recesses, and stationary annular insulating barriers between the brushes and 45 the rings, the inner edges of which are adjacent to the commutator cylinder.

10. In a dynamo-electric machine, the combination with a commutator cylinder comprising a plurality of insulated segments 50 and having annular recesses, metal bands or shrink rings for holding the segments in position, said bands or rings being insulated from the segments, of stationary supporting rods substantially parallel to the axis of the 55 commutator, brushes engaging the walls of the annular recesses, brush-supporting arms secured to the stationary rods, and annular barriers of insulating material also secured to the rods and having their inner edges located adjacent to the commutator cylinder and between the arms and the metal bands or rings.

In testimony whereof, I have hereunto subscribed my name this seventeenth day of 65 March, 1908.

SIEGFRIED VON AMMON.
